UNITED STATES PATENT OFFICE.

KENNEDY DOUGAN, OF MINNEAPOLIS, MINNESOTA.

TEMPERATURE REGULATOR.

1,420,916.

Specification of Letters Patent. Patented June 27, 1922.

Application filed October 25, 1919. Serial No. 333,419.

To all whom it may concern:

Be it known that I, KENNEDY DOUGAN, a citizen of the United States, and a resident of Minneapolis, in the county of Hennepin 5 and State of Minnesota, have invented certain new and useful improvements in a Temperature Regulator, of which the following is a specification.

One object of my invention is to provide 10 in temperature regulating means a device by which the heating effect of steam radiators or other containers in which the fluid is contained may be readily and easily varied.

Another object is to provide means for 15 regulating the level of liquid carried in the radiator whereby the radiating surface of the fluid, aside from the liquid itself, may be varied.

Another object is to provide in a device of 20 the class described multiple pipes of differing lengths and means whereby any one of these pipes may be connected to a drain pipe at will.

With these and incidental objects in view, 25 the invention consists of certain novel features of construction and combination of parts, the essential elements of which are hereinafter described with reference to the 30 drawings which accompany and form a part of this specification.

In the drawings, Figure 1 is a side elevation 35 of my improved device as connected to a radiator of the common type; Figure 2 is

a longitudinal section of the device shown 40 in Figure 1; Figure 3 is a section taken on the line 3—3, Figure 2; Figure 4 is a section taken on the line 4—4, Figure 2; Figure 5 is a section taken on the line 5—5, Figure 2;

Figure 6 is a longitudinal section of a modification of the device shown in Figures 1 to 45 5 inclusive; Figure 7 is a sectional detail of a modification of the means employed in rotating multiple pipes to align any one desired with the drain pipe; and Figure 8 is a section taken on the line 8—8, Figure 7.

As shown in Figures 1 and 2, the device is connected to a radiator or container 1 by nipples 2, which engage by screw connection 50 with the barrel 3 of the device.

A central pipe 4, having a closure 5 near the center thereof, engages by screw connection at 6 with a head 7, having packing rings 8 at the lower end thereof, and slideable 55 in the tube 9 joined to the barrel 3. A

header 10 is positioned near the head 7 with packing means 11 therebetween so the joint between the head 7 and header 10 will be kept fluid tight.

The header is feather keyed at 12 to the 60 barrel 3 to allow vertical movement therein and to prevent rotative movement therein.

A head 13 with packing nut 14 closes the 65 top of the barrel 3, allowing both rotative and slideable movement therein of the pipe 4.

The L-shaped arm 15 has journalled therein at 16 a shaft 17, having a thrust collar 17' thereon, the shaft engaging by screw connection with a cap 18 attached to the pipe 4, so the rotation of the crank 19 pinned to the 70 shaft 17 will raise or lower the pipe 4 and with it head 7 and header 10 which carries multiple pipes 20 of differing lengths.

A collar 21 surrounding the pipe 4 positions 75 therebetween a fingered collar 22 which is rotative on the pipe 4.

A forked lever 23, trunnioned at 24 on the 80 collar 22 has a lug 25 engageable with any one of the multiple notches 26 on the collar 21 so that by lowering the lever 23 and engaging the lug 25 with one of these notches the collar 21 and through it the pipe 4 with its multiple pipes 20 may be rotated. Hence any one of the multiple pipes 20 may be brought in line with the aperture 27 leading 85 through the passageway 28 and L 29 to the drain pipe 30, preferably leading to the boiler.

It is therefore evident that the radiator 1 may be supplied with water up to the level 90 of that one of the multiple pipes 20 in line with the aperture 27 and that the depth of the water in the radiator may be varied by bringing one of the multiple pipes 20 of a different length in line with the aperture 27. 95

Looking at Figure 3, it will be seen that 100 these multiple notches are numbered and the numerals thereon correspond with the multiple pipes and while the fingered collar 22 could not be rotated past the rib 22' of the arm 15 the pipe 4 may be rotated as much as possible by engaging the lug 25 with one of the notches, rotating the pipe 4 as first positioned, and then engaging the lug 25 with the next of the notches and continuing the 105 operation until the desired position of the pipe has been reached. The numerals are preferably so arranged that when the lever is positioned with the lug in the notch having the numeral of the pipe desired and the 110

fingered collar is brought snugly against the rib 22' the desired pipe will be in line with aperture 27.

It is also evident that if the crank 19 is 5 rotated the entire set of multiple pipes may be lifted through the desired distance, and hence if the total possible vertical lift is at least as great as the difference in length of the multiple pipes that the level of the liquid 10 in the radiator may be maintained at any required height.

As an alternate construction, I may fashion the top of the pipe 4' with a collar 31 Figure 7 and fasten to the extreme top thereof a 15 cap 32 with a rotatably mounted collar 33 positioned between the collar 31 and the cap 32. In this case the lever 23' is hinged at 34 on the collar 33 and engages at 35 with the cap 32 so the pipe 4' may be rotated by 20 turning the lever 23' in a horizontal plane in much the same way as the action of the lever 23 heretofore described.

The arm 15 has journalled therein the shaft 16' to which the crank 19 and also the 25 collar 17' are pinned, and as this shaft engages by screw connection with the cap 32 the rotation of the crank will raise or lower the pipe 4', this pipe being shown in Figure 7 in its fully raised position.

30 Referring again to Figure 2, the pipe 4 may be provided as at 36, with transverse apertures connecting with the central bore 37, leading to the passageway 28, thereby constituting the longest one of the multiple pipes, and it is evident that the longest 35 of the multiple pipes could be always left in connection with the drains so as to have a positive limit to the depth of the liquid in the radiator.

40 When, however, a large number of multiple pipes 20 are used there will always be one of the pipes in line with the aperture 27 so this transverse outlet would not be necessary.

45 In Figure 6 is shown a modification primarily designed for wheat heaters, and on account of the nature of the heating means the device hangs from the heater rather than extends above, and for convenience the regulating means are positioned on the lower end of the device.

In this modification the outlet drain pipe 30 connects directly into the flange pipe 38 fastened to the barrel 3', and the transverse aperture 36', if used, would lead to the annular space 39, to which the drain pipes 30 connect.

50 The lever 23 and crank 19 are the same as shown in Figure 2 but are positioned at the lower end of the device instead of the top thereof and connections from the multiple pipes 20 to the aperture 27' would be the same as heretofore described with respect to multiple pipes 20 and aperture 27, the pipe 4 having the head 7' thereon instead of this

head being positioned below the pipe as shown in Figure 2.

While I have described my invention and illustrated it in several particular designs, I do not wish it understood that I limit myself to these constructions, as it is evident that the application of the invention may be varied in many ways within the scope of the following claims.

Claims:

1. In a temperature regulator the combination with a fluid container, of a barrel, upper and lower pipe connections between said barrel and said fluid container, means in an operative position in said barrel for 70 limiting precisely the level of liquid and adjustable means controlling said level limiting means for setting said level limiting means at any desired height.

2. In a temperature regulator the combination of a barrel having apertures therein for connection to a heating device, a plurality of pipes of differing lengths positioned in said barrel, means for bringing any one of said pipes into line with an outlet, and means for raising or lowering said group of multiple pipes to any desired height with said outlet in an operative position.

3. In a temperature regulator the combination with a barrel, upper and lower apertures therein for connecting to a radiator or the like, a central pipe slidably and rotatably mounted in said barrel, a head positioned below said pipe and carried thereby and having an aperture therethrough leading to a drain outlet, a header positioned above said head and having a plurality of pipes of different lengths positioned vertically therein, said header being non-rotatable in respect to said barrel, means for rotating said pipe so as to bring the aperture in said head in line with any one of said multiple pipes, and means for raising and lowering said pipe, and with it said multiple pipes.

4. In a temperature regulator the combination with a barrel, of a centrally positioned pipe slidable and rotatable in said barrel, a plurality of pipes within said barrel and concentrically arranged around said first named pipe, said pipes varying in length, a collar having notches therein fixed to said pipe, a rotatable collar journalled on said pipe, a lever hinged to said rotatable collar and having a lug thereon adapted to engage with any one of said notches, whereby said pipe may be rotated to bring an aperture carried on a head below said pipes of varying lengths in line with any one of said pipes.

5. In a temperature regulator the combination with a barrel, of a centrally positioned pipe slidable and rotatable in said barrel, multiple pipes within said barrel and concentrically arranged around said first

- named pipe, said multiple pipes varying in length, a collar having notches therein fixed to said pipe, a rotatable collar journalled on said pipe, a lever hinged to said rotatable 5 collar and having a lug thereon adapted to engage with any one of said notches, whereby said pipe may be rotated to bring an aperture carried on a head below said multiple pipes in line with any one of said pipes, a 10 cap fixed to the upper end of said pipe, an L-shaped arm carried by said barrel, a shaft journalled in said L-shaped arm, a crank pinned on said shaft above said arm, a collar pinned on said shaft below said arm, said 15 shaft engaging, by screw connection, with said cap, whereby the rotation of said crank will raise or lower said central pipe, and with it said multiple pipes.
6. In a temperature regulator the combination of a plurality of pipes of different 20 lengths, a barrel surrounding said pipes, a head below said pipes having an aperture therein leading to an outlet, rotatable means
- for positioning said aperture in line with any one of said multiple pipes, and screw 25 actuated means for lifting said head and said multiple pipes.
7. In temperature regulating means the combination with a fluid container of a barrel having apertures therein for connection 30 to a heating device, a plurality of pipes of differing lengths positioned in said barrel, means for bringing any one of said pipes in a line with an outlet and raising or lowering 35 said group of multiple pipes.
8. In temperature regulating means the combination of a vertical fluid container having a fluid connection with a steam heater, a plurality of pipes of differing lengths vertically positioned in said fluid container, 40 means for raising and lowering said plurality of pipes and means for discharging fluid through any one of said pipes to a point outside of said steam container.

KENNEDY DOUGAN.
